TIE RACK

Russell W. Miles, Janesville, Iowa 50647

Filed Aug. 11, 1969, Ser. No. 18,641

Term of patent 14 years

Int. Cl. D6—01

U.S. Cl. D33—8

Fig. 1

Fig. 2

Fig. 3

Fig. 4

Fig. 5

FIG. 1 is a frontal perspective view of a tie rack showing my new design;

FIG. 2 is a side view thereof;

FIG. 3 is a front elevation thereof;

FIG. 4 is a top plan view thereof; and

FIG. 5 is a bottom plan view thereof.

I claim:

The ornamental design of a tie rack, substantially as shown.
